BACKGROUND OF THE INVENTION

1. Field of the Invention

With regard to the classification of art, this invention is believed to be found in the general class containing tools for applying a pushing or pulling force and more particularly to those subclasses pertaining to tools and methods for use with detachable vibratory railroad car shakers.

2. Description of Related Art Including Information Disclosed under 37 CFR 1.97 and 1.98

Detachable vibratory railroad car shaker apparatus are known in the field. Exemplary brackets for the removable mounting of a vibrator to a railroad car are disclosed in U.S. Pat. No. 3,003,733 that issued to Petersen on Oct. 10, 1961; and U.S. Pat. No. 3,463,431 issued to Matson on Aug. 26, 1969. These patents disclose a common type of separable male/female bracket arrangement. Usually the female portion of the bracket is attached to a hopper portion of a railroad car. This type of bracket is sometimes referred to as a Gardner or Tyler type and generally has C-shaped seat or pocket portion (i.e. a wedge, dovetail or the like.) The male portion generally may be characterized as a T-shape that has a blade member (i.e. male wedge, male dovetail or the like) and a reduced connector portion (i.e. web, neck, leg and the like) U.S. Pat. No. 3,003,733 also discloses a wedge shaped tool for separating the male portion from the female portion of the bracket. U.S. Pat. No. 5,779,427 that issued to Heffinger on Jul. 14, 1998 discloses a powered means for insertion and removal of the male portion or half of the bracket into the female portion or half of the bracket. U.S. Pat. No. 3,463,431 discloses a threaded means for retaining the male portion of the bracket in the female portion of the bracket.

As previously mentioned above, the female portion of the bracket is usually fixed to the railroad car by a suitable means such as welding and the like and therefore remains with the railroad car as it is moved to various yards, unloading sites or locations. Whereas the male half of the bracket is usually intended to remain at a particular site for unloading the railroad car. It can be appreciated that in use, the female portion of the bracket and the male portion may not be exactly mated because they come from different bracket manufacturers, car shaker manufacturers and/or in fact one or both of the parts of the bracket may be worn or oxidized. It can be also appreciated that the vibrator action may in fact cause the male and female portions to further lock together. Many times the male portion of the bracket is an integral part of the vibrator housing. It is common practice for a railroad work gang or crew to attempt to remove the vibrator from the car by means of a heavy hammer. It has been found that the railroad crews have bent the wedge disclosed in U.S. Pat. No. 3,003,733 thereby rendering it unusable for its intended use. If the crew is unsuccessful in removing the vibrator from the car, the vibrator will then travel with the railroad car to a new

location. The work gang or crew may or may not have a spare vibrator to attach to another railroad car to be unloaded. The work gang may never see the vibrator again. Any permanent loss of the vibrator results in a loss of 5 inventory and money. Permanent or temporary loss of a vibrator requires that spare vibrators be on hand thereby adding to operating costs. It has been determined that there is still a need to provide a tool that is useable with various combinations of male bracket portions and female bracket 10 portions. The desired tool must be easy to use and perform the function for which it has been made. The needed tool must also be economical to manufacture. The present invention provides such a tool and satisfies the identified need.

15 BRIEF SUMMARY OF THE INVENTION

The present invention may be briefly described with respect to its objects. It is an object of this invention to provide and it does provide a tool and method for its use that reliably releases, detaches or unseats a male portion of a bracket that is wedged or locked into a female portion of the bracket.

It is another object of this invention to provide and it does provide a tool that is economical to manufacture and use.

20 It is still another object of this invention to provide and it does provide a versatile tool and method for its use which may be used with various combinations of detachable mounting brackets for vibratory car shakers.

One embodiment of the present invention may be briefly 25 described as: a tool for use with a vibratory car shaker mounting bracket assembly, the mounting bracket assembly having a male blade portion that removably seats into a mating female pocket portion, the tool including: a) a cross bar member having a pair of first bar members attached thereto and extending therefrom in a substantially T-shaped 30 configuration, the first bar members being arrayed in a predetermined spaced relationship, the predetermined spaced relationship allowing for a straddling of a web or neck member of the male blade portion, each of the first bar members being elongated and having a major axis, each of the first bar members having at least one transverse aperture formed therein and therethrough and the transverse apertures being aligned in pairs on a common axis for forming an engagement means, the cross bar member further including 35 at least two threaded jacking means, preferably each threaded jacking means including a threaded aperture formed in the cross bar member. An axis of the threaded apertures being selectively aligned with the major axis of the first bar members for alignment with a selected surface of the female pocket portion of the mounting bracket assembly,

40 b) each of threaded jacking means further including an elongated threaded bolt being sized for mating with and threading into the threaded apertures of the cross bar member; c) an elongated pin member being sized to fit into the engagement means, the pin member further including at 45 least one removable retaining means, the pin member being of a sufficient length for being simultaneously engaged in the engagement means while being retained therein by the retaining means; and wherein the web or neck member of the male portion is selectively placed between the first bar members with the elongated threaded bolts being simultaneously aligned with the selected surface of the female portion, and the elongated pin member being selectively placed and retained by and in the engagement means so that 50 the elongated pin will abut a selected portion of the web member of the male portion as and when one end of each threaded jacking means is advanced to and towards the 55 engagement means.

selected surface of the female pocket portion thereby providing an urging force to provide relative movement of the male blade portion with respect to the female pocket portion.

The tool of the present invention also suggests a method for its use that may also be characterized as: a method of unseating a male blade portion from a female pocket portion of a separable mounting bracket assembly for a vibratory car shaker including the steps of: a) providing a tool having a substantially T-shaped configuration being formed by a pair of elongated first bar members that are fixed to a cross bar member, each of the pair of first bar members being selectively aligned and arrayed in a spaced relationship that is sufficient to straddle a web member of the male blade portion, the first bar members having an engagement means including a pair of transverse apertures selectively formed therein and therethrough on a common axis, the tool further including a pair of threaded jacking means and an elongated pin member, each threaded jacking means further including a threaded bolt being adapted for threading into a threaded aperture formed in the cross bar member, each threaded aperture being selectively aligned with a major axis of the first bar members, the elongated pin member having at least one removable retaining means; b) placing the tool onto and over the male blade portion so that the first bar members straddle the web member, while simultaneously and selectively aligning the one end of each threaded jacking means with a top surface of the female pocket portion; c) selectively inserting the elongated pin into the engagement means, then subsequently positioning the retaining means therein and thereon, d) advancing and urging the one end of each of the threaded jacking means against the top surface of the female pocket portion by threading the threaded bolts into the threaded apertures in substantially equal increments so that the elongated pin will abut a selected portion of the web member, subsequent and selective continued threading of the bolts into the threaded apertures causing relative movement between the male blade portion and the female pocket portion.

In addition to the above summary, the following disclosure is intended to be detailed to insure adequacy and aid in the understanding of the invention. However, this disclosure, showing particular embodiments of the invention, is not intended to describe each new inventive concept that may arise. These specific embodiments have been chosen to show at least one preferred or best mode of the present invention. These specific embodiments, as shown in the accompanying drawings, may also include diagrammatic symbols for the purpose of illustration and understanding.

BRIEF DESCRIPTION OF THE SEVERAL VIEW OF DRAWINGS

FIG. 1 represents a front elevation of a tool of the invention.

FIG. 2 represents a side elevation of the present invention.

FIG. 3 represents a top elevation of the present invention.

FIG. 4 represents a side elevation of present invention and its application or use.

FIG. 5 represents a front elevation of present invention in use, this view being taken along line 5—5 of FIG. 4.

FIG. 6 represent a side elevation of an alternate use for the present invention.

In the following description and in the appended claims, various components and details of construction are identified by specific names for convenience. These names are intended to be generic in their application while differenti-

ating between the various components and details. The corresponding reference numbers refer to like members throughout the several figures of the drawing.

The drawings accompanying and forming a part of this specification disclose details of construction for the sole purpose of explanation. It is to be understood that structural details may be modified without departing from the concept and principles of the invention as claimed. This invention may be incorporated into other structural forms than shown.

DETAILED DESCRIPTION OF THE INVENTION

Referring to the drawings and in particular to FIGS. 1 through 3, a tool assembly of the present invention is generally identified as 10. The tool assembly 10 includes a cross bar member 12 and a pair of first bar members 14 extending therefrom in a substantially T-shape configuration, as may be seen in FIG. 1. The first bars 14 are arrayed in a selected spaced relationship. The selected spaced relationship, its purpose and use will be discussed below. Preferably, the first bars 14 must be fixed or attached to the cross bar member 12 by a suitable attaching means such as welding or the like. Alternatively the cross bar member 12 and the first bar members 14 may be formed of a unitary construction such a molding or casting. It is also preferred that the cross bar member 12 and the first bar members 14 be formed of a structural metal that is suitable for the designed loading. The first bar members 14 may be characterized as having a major axis 16 that is elongated and may be more clearly seen in FIG. 2.

Each of the first bar members 14 includes at least one transverse aperture 18 that is formed therein and therethrough on the major axis 16. The transverse apertures 18 of each of the first bar members 14 are aligned on a common axis 20 and in pairs to form an engaging means 22. It has been found that providing the first bar members 14 with at least 2 pairs of engaging means 22 satisfies most applications of the tool of the present invention with known brackets. The transverse apertures 18 are sized for removably seating a pin member 24 therein. The pin member 24 should be of sufficient length so as to be engaged simultaneously by both first bar members 14 in a clevis-like fashion. The pin member 24 preferably includes at least one removable retaining means 26 such as a cotter pin, a hair pin cotter pin and the like. The pin member 24 may have two removable retaining means as shown in FIG. 1. Alternatively one end of the pin member 24 may include an enlarged head portion, seen in FIG. 5, that acts as a non-removable retaining means and the distal end of the pin member 24 is configured for a removable retaining means 26. As a second alternative, a threaded bolt and nut arrangement, not shown, may be substituted for the pin 24 and retaining means 26 that is depicted in the drawings.

Referring again to FIGS. 1-3, in this first and preferred embodiment of the tool 10, the cross bar members 12 further include a pair of threaded apertures 28 that are formed therein and therethrough. Each of the threaded apertures 28 includes a centerline or axis 30 that is offset a selected distance from the axis 16 of the first bar members 14. This selected offset distance and its use will be discussed below in connection with FIGS. 4-6. Threaded bolts 32 having a selected length and size are positioned in the threaded apertures 28 in a conventional manner to form a threaded jacking means 34. Alternatively the threaded jacking means 34 may include a threaded bolt 32 that is guided by a through non-threaded aperture in the cross bar member 12 rather

than a threaded aperture **28**. In this alternate arrangement at least one threaded nut **33**, shown in dashed outline, will be positioned on the threads of the bolt **32** so that one end of the bolt is advanced in a jacking fashion in the direction of arrow A. It is preferred that a reinforcing means **36** be also provided such as cast or molded pads, metal blocks or bars and the like that reinforce the attachment of the first bars **14** to the cross bar member **12**. It is also preferred that the reinforcing means **36** be arrayed to provide a space or gap **38**. This reinforcing means **36** will also provide a greater length for a guiding or bearing surface for the threaded bolt **32**. The space or gap **38** and its purpose will be discussed below.

USE AND OPERATION

Referring now to FIGS. 4 and 5, a mounting bracket generally identified as **40**, shown in dashed outline, is provided for removably attaching or mounting a vibratory car shaker **42** to a wall **44** of a railroad car. The mounting bracket **40** generally includes a female portion **46** and a male portion **48**. The mounting bracket **40** is commonly known as a Gardner or Tyler type. This type of mounting bracket may also be known as a wedge type, dove-tail-type and the like. The female portion **46** generally includes a C-shaped pocket portion **50** into which a T-shaped male blade member **52** of the male portion **48** is seated. The male portion **48** further includes a web, leg or neck portion **54** that is smaller in width than the blade member **52**. The web **54** connects the vibrator **42** to the male blade member **52**. The male portion **48** of the bracket **40** may be cast as an integral part of a vibrator **42**. One non-limiting example of this type of integral arrangement is Model CCW-5000 manufactured by Vibco Inc., Wyoming RI. Model CCW-5000 may also include an integral cast handle **56**. The male blade member **52** may be configured as a self-locking wedge.

Still referring to FIGS. 4 and 5, the tool assembly **10**, with the pin member **24** removed and one end **62** of each jacking means **34** in a retracted condition, is placed onto and over the web member **54**. The web member **54** is straddled by the spaced first bar members **14**, seen more clearly in FIG. 5. The spacing should be sufficient to allow easy straddling thereof while allowing a selected clearance therebetween. It has been found that a spacing in the neighborhood of 3.8 cm (1.5 in.) has provided satisfactory results with known brackets. The notched area or gap **38** provides clearance for the integral handle **56** of the vibrator **42** or a protruding portion of the web member **54** to pass therethrough. A notched area or gap **38** in the neighborhood of 2.5 cm. (1.0 in.) wide has been found to provide good results with known brackets. The pin member **24** is placed in a selected engagement means **22**. The engagement means **22** may be aligned with a through aperture **58** in the web **54** or may be aligned with a bottom edge **60** of the web portion. Subsequently the removable retaining means **26** is positioned into the pin member **24**. Finally one end **62** of each of the threaded jacking means **34** is advanced in substantially equal increments to and towards a selected surface **64** of the female portion **46** to cause a substantially uniform relative movement, absent cocking, between the male portion **48** and the female portion **46**. It is to be noted that the offset distance between axis **30** and major axis **16** must be sufficient for allowing engagement of the web member by the pin member while allowing the relative movement, in the direction of arrow B, of the male portion **48** with respect to the female portion **46**. As a non-limiting example, it has been found that an offset distance in the neighborhood of 3.2 cm (1.25 in.) between major axis **16** and axis **30** has provided good results

with known brackets when the major axis **16** is centrally located in a 3.2 cm. (1.25 in) wide first bar member **14**. This example of an offset results in a throat distance of 1.6 cm (0.625 in.).

As it was previously mentioned, the mounting bracket **40** is generally of a self-locking type and usually requires a forceful separation of the male portion **48** from the female portion **46**. However if the male portion **48** does not self lock into the female portion **46**, the tool of the present invention may be adapted for use in helping to maintain the engagement or seating of the male portion **48** within the female portion **46** by being applied in a reverse manner as shown in FIG. 6. The pin member **24** may be positioned in a through aperture in the web, similar to **58** when a handle **56** is present or abutted against a top edge **64** of the web or neck **54** when a handle is not present. The one end **62** of the jacking means **34** could be selectively advanced to abut a bottom surface **66** of the female portion **46** thereby providing the desired retention. In this arrangement at least one standard type of locking threaded nut, shown in dashed outline, should be used on each jacking means **34** for maintaining the set position.

Directional terms such as "front", "back", "in", "out", "downward", "upper", "lower" and the like may have been used in the description. These terms are applicable to the embodiments shown and described in conjunction with the drawings. These terms are merely used for the purpose of description in connection with the drawings and do not necessarily apply to the position in which the present invention may be used.

While these particular embodiments of the present invention have been shown and described, it is to be understood that the invention is not limited thereto and protection is sought to the broadest extent that the prior art allows.

What is claimed is:

1. A tool for use with a vibratory car shaker mounting bracket assembly, said mounting bracket assembly having a male blade portion that removably seats into a mating female pocket portion, said tool including:
  - a) a cross bar member having a pair of first bar members attached thereto and extending therefrom in a substantially T-shaped configuration, said first bar members being arrayed in a predetermined spaced relationship, said predetermined spaced relationship allowing for a straddling of a web member of the male blade portion, each of said first bar members being elongated and having a major axis, each of said first bar members having at least one transverse aperture formed therein and therethrough and said transverse apertures being aligned in pairs on a common axis for forming a pin engagement, the cross bar member further including at least two threaded jacks carried therein and therethrough, an axis of said threaded jacks being selectively aligned with the major axis of the first bar members for alignment with a selected surface of the female pocket portion of the mounting bracket assembly,
  - b) each of said threaded jacks further including a female threaded portion and an elongated threaded bolt being sized for mating with and engaging therein and therethrough;
  - c) an elongated pin member being sized to fit into the pin engagement, said pin member further including at least one removable retainer, said pin member being of a sufficient length for being simultaneously engaged in the pin engagement while being retained therein by the retainer; and

wherein the web member of the male portion is selectively placed between the first bar members with the elongated threaded bolts simultaneously aligned with the selected surface of the female portion, and said elongated pin member being selectively placed and retained by and in the pin engagement so that the elongated pin will abut a selected portion of the web member of the male portion as and when one end of said threaded bolts are advanced to and towards the selected surface of the female pocket portion by rotation of the threaded jacks for providing relative movement of the male blade portion with respect to the female pocket portion.

2. A tool as recited in claim 1 wherein the female threaded portion of each threaded jack is a threaded aperture in the cross bar member. 15

3. A tool as recited in claim 1 wherein said female threaded portion is a threaded nut.

4. A tool as recited in claim 1 wherein said pin member further includes an enlarged head portion and an end of said pin member distal to said enlarged head portion carries said removable retainer. 20

5. A tool as recited in claim 2 wherein said pin member further includes an enlarged head portion and an end of said pin member distal to said enlarged head portion carries said removable retainer. 25

6. A tool as recited in claim 3 wherein said pin member further includes an enlarged head portion and an end of said pin member distal to said enlarged head portion carries said removable retainer. 30

7. A tool as recited in claim 1 wherein said pin member includes two retainers, one of said retainers being removably mounted in a first end of said pin member and a second of said retainers being removably mounted in a second end of said pin member. 35

8. A tool as recited in claim 2 wherein said pin member includes two retainers, one of said retainers being removably mounted in a first end of said pin member and a second of said retainers being removably mounted in a second end of said pin member. 40

9. A tool as recited in claim 3 wherein said pin member includes two retainers, one of said retainers being removably mounted in a first end of said pin member and a second of said retainers being removably mounted in a second end of said pin member. 45

10. A tool as recited in claim 1 wherein a reinforcement is provided for reinforcing a connection of the each first bar member to the cross member. 45

11. A tool as recited in claim 2 wherein a reinforcement is provided for reinforcing a connection of the each first bar member to the cross member. 50

12. A tool as recited in claim 3 wherein a reinforcement is provided for reinforcing a connection of the each first bar member to the cross member.

13. A tool as recited in claim 1 wherein said tool includes a selectively sized notched area that is formed therein and thereon, said notched area being of a selected size and central to said predetermined spaced relationship of said first 55

bar members for allowing a protruding portion of said male blade portion to pass therethrough.

14. A tool as recited in claim 2 wherein said tool includes a selectively sized notched area that is formed therein and thereon, said notched area being of a selected size and central to said predetermined spaced relationship of said first bar members for allowing a protruding portion of said male blade portion to pass therethrough.

15. A tool as recited in claim 3 wherein said tool includes a selectively sized notched area that is formed therein and thereon, said notched area being of a selected size and central to said predetermined spaced relationship of said first bar members for allowing a protruding portion of said male blade portion to pass therethrough.

16. A method of unseating a male blade portion from a female pocket portion of a separable mounting bracket assembly for a vibratory car shaker including the steps of:

a) providing a tool, said tool having a substantially T-shaped configuration formed by a pair of elongated first bar members that are fixed to a cross bar member, each of the pair of first bar members being selectively aligned and arrayed in a spaced relationship that is sufficient to straddle a web member of the male blade portion, said first bar members having a pin engagement formed by a pair of transverse apertures selectively formed therein and therethrough on a common axis, said tool further including a pair of threaded jacks and an elongated pin member, each of said threaded jacks including a threaded bolt being adapted for threading into a female portion of said threaded jacks, each of said threaded jacks being carried in and by the cross bar member, each of said threaded jacks being selectively aligned with a major axis of the first bar members, said elongated pin member having at least one removable retainer;

b) placing said tool onto and over the male blade portion so that the first bar members straddle said web member, while simultaneously and selectively aligning one end of said threaded bolts with a top surface of the female pocket portion;

c) selectively inserting said elongated pin into said pin engagement, then subsequently positioning said retainer therein and thereon,

d) urging said one end of said threaded bolts against said top surface of the female pocket portion by rotation of one portion of said threaded jacks so that the elongated pin will abut a selected portion of the web member, subsequent and selective continued rotation of each threaded jacks causing a uniform relative movement between said male blade portion and said female pocket portion.

17. A method as recited in claim 16 wherein the female threaded portion of the threaded jacks is a threaded aperture in the cross bar member.

18. A method as recited in claim 16 wherein said female threaded portion is a threaded nut.
